UNITED STATES PATENT OFFICE.

GAILORD M. HINER AND LOGAN L. HIDY, OF JEFFERSONVILLE, OHIO.

APPARATUS FOR SWAGING SEAMLESS CROWNS.

1,168,212.

Specification of Letters Patent. Patented Jan. 11, 1916.

Application filed February 10, 1915. Serial No. 7,426.

To all whom it may concern:

Be it known that we, GAILORD M. HINER and LOGAN L. HIDY, citizens of the United States, residing at Jeffersonville, in the 5 county of Fayette and State of Ohio, have invented certain new and useful Improvements in Apparatus for Swaging Seamless Crowns; and we do hereby declare the following to be a full, clear, and exact description 10 of the invention, such as will enable others skilled in the art to which it appertains to make and use the same.

This invention relates to apparatus for swaging seamless crowns, and one of the 15 principal objects of the invention is to provide an apparatus of comparatively simple construction which will quickly and efficiently form a seamless crown of gold or other material.

Another object of the invention is to provide an apparatus of comparatively simple construction for forcing a sectional inner or counter die outward against the inner walls 20 of a die to press the seamless crown between 25 the dies so that it will take the exact contour of the outer die upon the outer side and the inner die upon its inner side, the means for forcing the counter die outward being in the form of a wedge or expanding 30 tool.

The foregoing and other objects may be attained by means of the construction illustrated in the accompanying drawing, in which—

Figure 1 is a view in side elevation of an apparatus for expanding crowns made in accordance with this invention, Fig. 2 is a perspective view of the sectional outer die, Fig. 3 is a detail perspective view of a portion 35 of an expanding tool used in connection with the apparatus, Fig. 4 is a sectional view taken through a portion of the bed block, and through the sectional outer and inner dies with an expander in place and 40 showing the seamless crown in position between the inner and outer dies, Fig. 5 is a detail perspective view of a portion of an expanding tool of slightly modified form, Fig. 6 is a perspective view of the two members 45 of the inner die, and Fig. 7 is a perspective view of a seamless crown, such as is made on the apparatus shown in Fig. 1.

Referring to the drawing, the numeral 1 designates the base portion of a suitable 55 press, and 2 are the spaced arms of the same, connected by a cross bar or cross head 3.

Mounted on the cross head is a casing 4, in which is pivoted a cam lever 5, said lever having a cam or eccentric head 6 pivoted at 7 and adapted to bear upon the upper end 60 of a shaft 8 which extends through the cross head 3 and through the enlargement 9 thereon. A spiral spring 10 encircles the shaft and is connected at one end thereto, while the other end bears against the enlargement 65 9, said spring serving to retract the shaft 8, while the eccentric head 6 of the cam lever is adapted to force the shaft downward.

The character of the press to be used in connection with this invention may be varied 70 within wide limits.

Connected to the shaft 8 preferably by means of a pin 11 is an expanding tool 12 having a tapering or wedge-shaped end 13, which may be provided with dove-tail portions 75 14, one upon each side of the wedge 13. As shown in Fig. 5, the expanding tool 12 may be provided with a plain wedge-shaped end 13^a, the dove-tail portions 14 being omitted, and for some kinds of work 80 this tool is to be preferred to the one previously described.

The bed block is preferably made of wood and of two sections 15 and 15^a, the section 15^a being provided with a guide or keeper 85 16 which engages one of the arms 2 of the press. The two sections of the bed block are held in intimate connection by means of a binding screw 17 extending through one of the arms 2 and provided with a swiveled 90 bearing member 18. The screw 17 is provided with a winged thumb piece 19. Fitted in an opening 20 in the bed blocks 15, 15^a are the sections 21 of the outer die, said 95 sections having their inner walls 22 and the bottom 23 formed to the exact contour 100 of the outer surface of the crown *a*. The inner dies 24 are made in two sections with their outer surfaces conforming to the contour of the inner walls 22 of the die 21. The inner dies 24 are provided with recesses 105 25 which may be wedge-shaped or dove-tail, as shown in Fig. 6 of the drawing.

The manner of using the apparatus may be briefly described as follows: The sheet 105 metal or gold of which the crown *a* is formed is of uniform gage or thickness and is placed within the die members 22 and the inner dies 25 are placed within the crown. The two dies are then placed in the bed blocks 15 110 and 15^a and the expanding tool is inserted between the two members of the inner die

and forced downward by means of the lever 5.

From the foregoing it will be obvious that the process of making the crowns is comparatively quick and is efficient for the purpose of forming a seamless crown which will conform exactly to the tooth for which it is made. It will be understood of course that the crowns can be made for any form 10 of tooth.

Various changes may be made in the details of construction without departing from the spirit and scope of the invention as defined in the claims.

15 What is claimed is:—

1. An apparatus for forming seamless crowns which comprises a sectional outer die, a sectional inner die, an expanding tool adapted to engage the inner surfaces of the inner die for crowding them outward to form a crown between the inner and outer dies, said expanding tool having a wedge-shaped end, and said inner die being recessed to receive the wedge.
- 20 2. An apparatus for swaging seamless crowns comprising a bed block having a recess therein and formed of two sections,
- 25 3. An apparatus for forming seamless crowns comprising a press having a shaft mounted therein, a spring for raising said shaft, a cam lever for depressing said shaft, a bed block, an outer die mounted in the bed block, an inner die mounted in the outer die, and an expanding tool adapted to enter between the inner dies, said expanding tool having a wedge-shaped end to force the inner die members outward and form a crown 45 between said inner dies and outer dies.

means for holding said sections together, a die made in two sections and fitted in the aperture between the bed block sections, an 30 inner die, and an expanding tool to fit between the two members of the expanding die and crowd the members outward against a crown blank between the inner and outer dies.

35 3. An apparatus for forming seamless crowns comprising a press having a shaft mounted therein, a spring for raising said shaft, a cam lever for depressing said shaft, a bed block, an outer die mounted in the bed block, an inner die mounted in the outer die, and an expanding tool adapted to enter 40 between the inner dies, said expanding tool having a wedge-shaped end to force the inner die members outward and form a crown 45 between said inner dies and outer dies.

In testimony whereof we affix our signatures in presence of two witnesses.

GAILORD M. HINER.
LOGAN L. HIDY.
